CORN AND CALLUS TRIMMER

Claud L. Potvin, Minneapolis, Minn.

Application September 13, 1951, Serial No. 246,465

6 Claims. (Cl. 30—26)

1

This invention relates to new and useful improvements in corn and callus trimmers of the general type disclosed in my co-pending application, Ser. No. 28,292, filed May 21, 1948, which issued on October 30, 1951 as Patent No. 2,573,487.

An important object of the present invention is to provide a corn and callus trimmer comprising a simple, inexpensive blade having means for demountably securing it in operative position in the head of the device, whereby it may readily be removed for sharpening, when desired, or discarded to permit the substitution of a new blade therefor.

A further object is to provide a corn and callus trimmer comprising a simple, inexpensive flat blade having a spring clip for securing it in position on its seat, and whereby it is firmly held thereon.

Other objects reside in the novel design of the device, whereby it may readily be molded from plastic material to provide a very neat and attractive device of this general type which readily lends itself to manufacture in quantity production at extremely low cost; in the specific construction of the head of said device, whereby a portion thereof provides, in effect, a window through which the user may readily note the action of the blade when moving it into cutting engagement with a corn or callus; and in the unique construction of the blade and its retaining clip, whereby the blade may readily be secured in position in the head of the device or removed therefrom without the use of a separate tool.

These and other objects of the invention and the means for their attainment will be more apparent from the following description taken in connection with the accompanying drawings.

In the accompanying drawings there has been disclosed a structure designed to carry out the various objects of the invention, but it is to be understood that the invention is not confined to the exact features shown, as various changes may be made within the scope of the claims which follow.

In the drawings:

Figure 1 is a perspective view of the device showing a blade secured in operative position therein;

Figure 2 is a plan view of Figure 1;

Figure 3 is a detail sectional view on the line 3—3 of Figure 2, showing the position of the cutting edge of the blade relative to the bottom face of the head;

Figure 4 is a plan view of one end of the device with the blade removed therefrom;

Figure 5 is an edge view of Figure 4, showing the longitudinally extending ribs provided on the bottom face of the head for facilitating the operation of guiding the instrument over the surface of a corn or callus;

2

Figure 6 is a perspective view of the blade retaining clip detached from the trimmer;

Figure 7 is a view showing the preferred shape of the blade; and

Figure 8 is a view showing a modified construction wherein the blade is of rectangular form.

The novel corn and callus trimmer herein disclosed is shown comprising an elongated body, generally designated by the numeral 2, having an enlarged head 3 at one end, and the remaining portion thereof providing a handle 4, for facilitating the operation of manually moving the cutting edge of the blade over the surface of a corn or callus.

The head 3 has a recess 5 therein having a horizontal transparent bottom wall 10 at its forward end providing a window through which the operator may readily view the corn or callus over which the head 3 of the instrument is moved in the operation of trimming a corn or callus. The rear wall or edge 6 of the window portion 10 defines one side of an elongated slot 7, the opposite side of which is defined by the lower edge 8 of the rear inclined bottom wall 9 of the recess 5, as will readily be understood by reference to Figure 3.

The upper inclined surface 11 of the wall portion 9 constitutes a seat for a knife blade 12, which preferably is in the form of a parallelogram, as illustrated in Figure 7. The blade has an edge 13 which is aligned with the slot 7, when the blade is positioned on its seat 11, as illustrated in Figure 2, the angle of the slot corresponding to the angle of the cutting edge of the blade 12.

An important feature of the present invention resides in the means provided for removably supporting the knife blade in the head 3, whereby it may readily be removed therefrom for sharpening, when desired, or when a new blade is to be substituted for one that has become worn.

The means provided for thus securing the knife blade in the head is best illustrated in Figures 3 and 6, and comprises a metallic spring clip, generally designated by the numeral 14. The clip is provided at its forward end with an upturned hook 15 adapted to be received in a small slot or opening 16 provided in the intermediate portion of the blade 12, as shown in Figures 1, 2 and 3. An elongated recess 17 is provided in the upper rear portion of the head 3 for receiving the clip 14, when in blade-locking engagement with said head. The rear end of clip 14 is shown bent downwardly, forwardly, and rearwardly, to provide a finger-engaging member 18 having a forwardly extending portion 19 adapted to be received in an indentation 21 provided in the rear vertical edge of the head, as indicated in Figures 2, 3 and 4, thereby to frictionally retain the clip 14 in blade locking engagement with the head, when

the device is to be used for trimming a corn or the like.

To assure that the blade cannot relatively shift its position in the head 3, when the tool is in use, an abutment shoulder 22 is provided at the upper end of the inclined seat 11 adapted to be engaged by the upper edge 23 of the blade when the latter is operatively positioned in the head of the trimmer. If deemed necessary, the shoulder 22 may be slightly undercut so as to 10 overlie the edge of the blade to prevent the latter from accidentally lifting from its seat, when the cutting edge of the blade is moved into cutting engagement with a corn or callus.

To secure the blade in position in the head, the hook 15 of the forward end of the clip 14 is inserted through the opening 16 in the blade, and the blade is then placed on the seat 11 with the free end of the clip positioned substantially as indicated in dotted lines in Figure 3. The rear portion 19 of the clip may then be pressed into locking engagement with the indentation 21 of the head with a snap action, whereby the tension in the clip will draw the upper edge of the blade firmly into engagement with the shoulder 22 so that the blade cannot possibly relatively shift its position in the head when the tool is in use.

It will be noted by reference to Figures 1 and 2 that the opposed side walls of the recess 5 coincide substantially with the corresponding side edges of the blade, whereby said edges cooperate with the shoulder 22 to prevent any possibility of the blade relatively rotating or shifting its position in the head when secured therein. The head 3 is shown provided with spaced ribs 28 and 30 adapted to engage the anatomy of the patient adjacent to the sides of the corn or callus to facilitate moving the knife edge over the surface thereof.

In a tool of the character herein disclosed, it is essential that the cutting edge of the blade be maintained sharp at all times to facilitate trimming the surface of a corn or callus with a minimum of effort. Should the blade become dulled, it may be resharpened for further use, but ordinarily it is discarded and a new blade substituted therefor because of the simple and inexpensive construction of the blades, whereby they may be purchased at extremely low cost in a manner similar to conventional safety razor blades.

The entire body 2 of the trimmer, including the head 3 and the handle 4, is preferably constructed of a suitable transparent plastic material of which there are now several readily available, thereby providing such a device which is substantially self-cleaning and attractive in appearance.

In Figure 8 there is illustrated a slightly modified construction wherein the blade 24 is rectangular in configuration and has a cutting edge 25 aligned with a slot 26, corresponding to the slot 7 in the form shown in the previous figures. The form shown in Figure 8 has a head 27 and a handle portion 28, and a clip 29 having a hook 31 and a finger-engaging member 32 is provided for removably securing the blade 24 on its seat in the head 27.

The foregoing detailed description has been given for clearness of understanding only, and no unnecessary limitations should be understood

therefrom, but the appended claims should be construed as broadly as permissible in view of the prior art.

I claim as my invention:

1. In a device for trimming corns, calluses, and the like, comprising an elongated body provided at one end with an enlarged head having a recess therein terminating at its bottom in an elongated opening disposed obliquely to the longitudinal axis of the head, said recess having an inclined blade supporting wall, the lower edge of which defines one side of said elongated opening, a knife blade having a cutting edge on one end seated on said inclined wall with its cutting edge projecting slightly through said elongated opening, and a spring clip having one end engaged with said blade and having means at its opposite end adapted to interlock with means on a wall of said head, thereby to detachably secure the blade in operative position in said head.

2. A corn and callus trimmer according to claim 1, wherein the blade is flat and has a cutting edge at its forward end.

3. A corn and callus trimmer according to claim 2, wherein the spring clip has a hook at its forward end receivable in an opening in the blade, and the opposite end of said clip having a downwardly and forwardly extending portion adapted to be received in an indentation in a wall of the head by a snap action, when pressure is applied to said clip.

4. In a device for trimming corns, calluses, and the like, comprising an elongated body provided at one end with an enlarged head having a recess therein comprising an inclined bottom wall portion and a horizontal bottom wall portion, said wall portions having their contiguous edges spaced apart to provide an elongated opening disposed obliquely to the longitudinal axis of the head, a flat knife blade seated on said inclined bottom wall portion and having a cutting edge projecting through said elongated opening and slightly below the bottom surface of the head, the upper end of said inclined bottom wall portion terminating in an elongated shoulder adapted to be engaged by the rear edge of the blade when secured in said head, a spring clip having an upturned hook at its forward end receivable in an opening in the intermediate portion of the blade, and means on the opposite end of said clip for lockingly engaging the rear wall of the head with a snap action, and whereby the clip is placed under tension to firmly retain the blade on said inclined wall portion with its rear edge engaged with said longitudinal shoulder.

5. A corn and callus trimmer according to claim 4, wherein the horizontal bottom wall portion of said recess is transparent to enable the operator to view the action of the knife blade on the corn or callus being trimmed.

6. A corn and callus trimmer according to claim 4, wherein the spring clip is received in a recess extending rearwardly from said inclined wall, whereby said clip when in blade-securing engagement with the head, will exert a force on said blade to firmly retain it in engagement with said inclined wall portion and the shoulder provided at the upper rear end thereof.
